[57] CLAIM

The ornamental design for an electric radiant space heater, as shown and described.

DESCRIPTION

FIG. 1 is a front perspective view of an electric radiant space heater embodying our design;

FIG. 2 is a side elevational view thereof;

FIG. 3 is a top plan view thereof;

FIG. 4 is a bottom plan view thereof.

The side of the heater opposite that viewed in FIG. 1 is the same in appearance as FIG. 1, as the same is suggested in FIGS. 2, 3 and 4.

FIG. 1

FIG. 2

FIG. 3

FIG. 4
